ASSIGNORS TO: WESTERN ELECTRIC COMPANY, INCORPORATED, OF NEW YORK,
N. Y., A CORPORATION OF NEW YORK.

METHOD AND SYSTEM FOR AMPLIFYING VARIABLE CURRENTS.

Application filed April 9, 1918. Serial No. 227,564.

To all whom it may concern:

Be it known that we, GUSTAF W. ELMAN and CARL F. ORT, citizens of the United States and subject of the Emperor of Austria, respectively, residing at Bogota, in the county of Bergen, State of New Jersey, and at New York, in the county of New York, State of New York, respectively, have invented certain new and useful Improvements in Methods and Systems for Amplifying Variable Currents, of which the following is a full, clear, concise, and exact description.

This invention relates to methods of and systems for amplifying variable currents and more particularly to signaling systems in which alternating currents are subjected to the action of a variable impedance.

An object of the invention is to provide a method of increasing the permeability of magnetic material.

Another object of the invention is to provide means for rapidly changing the permeability of magnetic cores for alternating fluxes at initial low flux densities.

A further object of the invention is to provide a variable alternating current impedance, the value of which may be readily controlled.

A still further object of the invention is to provide means for amplifying weak signaling currents.

It is well known that if a core of magnetic material is made a path for alternating fluxes of different frequencies the higher frequency flux takes over the work of hysteresis. It has been discovered that not only is the hysteresis effect for the low frequencies reduced, but the permeability of the magnetic material at low flux densities is considerably increased by the presence of the higher frequency flux. It is found that for a given value of high frequency flux, the permeability for the low frequency flux increases very rapidly with increasing density of the low frequency flux and reaches a maximum value at a relatively low density, after which the permeability decreases.

According to this invention the circuit of the current which is to be amplified includes the primary winding of a magnetic device which comprises a toroidal core of magnetic material. A second winding associated with

the same core is included in the circuit of a source of alternating current of frequency lower than that of the current which is to be amplified. Variation of the weak signaling current in the input circuit varies the high frequency flux produced thereby and correspondingly changes the permeability of the magnetic core for the flux set up by the lower frequency current flowing in the output circuit. An increase in the permeability of the core, and therefore in the magnetic flux produced by the low frequency current, increases the induction and therefore the impedance of the portion of the lower frequency circuit directly associated with the core, while decrease in the permeability of the core results in decrease in the impedance of this portion of the lower frequency circuit.

In the drawing, Fig. 1 illustrates a wire signaling system, while Figs. 2 and 3 illustrate respectively a transmitting station and a receiving station for radio signaling. Referring to Fig. 1, a generator 1 producing oscillations of high frequency r at a transmitting station A is shown connected in a series circuit including the microphone 2, a variable resistance 3 and windings 4 and 5 respectively of toroidal magnetic cores 6 and 7. A generator 8 of oscillations of frequency q is connected by a potentiometer 9, in a circuit 10 including windings 11 and 12 of toroidal cores 6 and 7 respectively, a variable inductance 13 and a variable capacity 14. Circuit 10 extends to a receiving station B and includes the primary winding of a transformer 15, the secondary winding of which is included in the receiving circuit. As shown in the drawing, circuit 10 is grounded as at G at both the receiving and transmitting stations. This arrangement may obviously be replaced by one employing a metallic return conductor.

The secondary winding of transformer 15 is connected through a detector D to a telephone receiver R which is shunted by the usual condenser C.

In operation the microphone 2 serves to vary, in accordance with signals, the amplitude of the oscillations of frequency r supplied by the circuit of generator 1. The varying amplitude oscillations pass through the windings 4 and 5 which are connected

in opposition with respect to the windings 11 and 12 and accordingly no current of frequency r is set up in circuit 10, since the electromotive forces induced in windings 11 and 12 are oppositely directed and equal to each other. The number of turns of windings 11 and 12 may be so chosen that these electromotive forces completely neutralize each other. Windings 11 and 12 are supplied by generator 8 with oscillations of frequency q which is preferably much lower than frequency r . Circuit 10 may be tuned as desired by means of variable inductance 13 and variable capacity 14. Current 16 through windings 11 and 12 gives rise to a flux in cores 6 and 7, the value of which is dependent upon the permeability of these cores for flux of frequency q . When these cores are subjected to higher frequency flux, such as that resulting from the oscillations of frequency r , the hysteresis energy which it is necessary to supply for maintenance of the low frequency flux, is much reduced. If, by proper design of the cores 6 and 7 and windings 11 and 12, the density of the flux of frequency q is kept relatively low, the higher frequency flux has the further effect of markedly changing the permeability for the flux of frequency q . This causes 30 a corresponding change in the inductance and therefore in the impedance of windings 11 and 12 for alternating current of frequency q , and the variations in the amplitude of this current are attended with corresponding variations in the current in the receiver circuit at station B. Preferably the density of the flux of frequency q should be maintained within the range throughout which the high frequency flux produces the 35 most rapid change in permeability. If q is an ultra audible frequency, the detector D will set up in the circuit of the receiver a low frequency signaling current corresponding to the variations set up by microphone 2 in the current of the circuit of generator 1.

The function of the magnetic cores 6 and 7 and their associated windings is in this instance to enable modulation of the current of circuit 10 in accordance with signaling 40 currents. Viewed broadly, however, the magnetic device serves to amplify variations in electric current. This arrangement is therefore of general application as an amplifier.

55 In the system of Fig. 2, the generator 16 supplies oscillations of frequency r to a circuit including a microphone or other transmitting device 17, a current regulating resistance 18 and windings 19 and 20 of toroidal magnetic cores 21 and 22 respectively. A generator 23 supplies oscillations of frequency q , which is considerably lower than frequency r , to a circuit including windings 24 and 25 of cores 21 and 22 respectively, 50 variable capacity 26 and primary winding of a transformer 27. Windings 19 and 20 are wound on cores 21 and 22 in opposition with respect to the windings 24 and 25 as in the case of the system of Fig. 1. Capacity 26 permits tuning of the circuit of generator 23, as for example, to the frequency q or to the mean frequency of any band frequencies which it may be desired to transmit.

The secondary winding of transformer 27 is included in series with tuning condenser 75 28 in the circuit of antenna 29 which serves to radiate electromagnetic waves corresponding to oscillations modulated in accordance with signals.

The operation of the system of Fig. 2 is 80 analogous to that of Fig. 1, with the exception that ungridded electromagnetic waves are transmitted in the system of Fig. 2 and the frequency q should therefore be made such as to permit of efficient radiation.

85 Referring to the radio receiving system of Fig. 3, the circuit of antenna 30 includes the tuning condenser 31 and windings 32 and 33 of magnetic cores 34 and 35 respectively. Windings 36 and 37 of cores 34 and 35 constitute two diagonally opposite arms of a Wheatstone bridge of which the other arms are windings 38 and 39 of cores 40 and 41. The generator 42 connected through a series tuning condenser 47 to the diagonally opposite corners 43 and 44, supplies electrical oscillations of frequency s to the Wheatstone bridge. Connected between the other two corners of the Wheatstone bridge is conductor 45 which includes the primary winding 100 of the transformer 46. The input winding of a detector 'D', preferably of the vacuum tube type, serves as the secondary of transformer 46 and the output winding of the detector is coupled to the local circuit of 105 receiver R'.

110 The operation of this receiving system will now be described. Incoming waves modified or modulated, as the case may be, in accordance with signals, set up high frequency oscillations in the antenna circuit. If the frequency of such oscillations be q , cores 34 and 35 will be subjected to alternating flux of frequency q . At any time when no signals are being transmitted, the 115 Wheatstone bridge is balanced for oscillations supplied by the generator 42, such balancing being readily accomplished by making the cores 34, 35, 40 and 41 alike and by properly choosing the constants of 120 each bridge arm, including the number of turns of the core windings. During non-signaling periods, no current will flow through conductor 45. During periods of incoming signals, the high frequency flux varies the impedance of windings 36 and 37 to the lower frequency current s in accordance with the variations in the incoming signal oscillations. The resulting unbalance causes current of frequency s to flow 125 130

in conductor 45 and a response corresponding to the original signals is obtained in receiver R'.

The frequencies of the oscillations supplied to the primary and secondary windings of the magnetic amplifying device may take a wide range, provided only that the input current have a considerably higher frequency than the output current. As a specific example, the frequency r may be 200,000; q may be 50,000 and s may be 10,000 cycles per second.

In the circuits of each of the three figures of the drawing, the amplifying arrangement is substantially the same and consists of a magnetic core device having an input circuit winding and an output circuit winding. The input winding is supplied with high frequency oscillations varied in accordance with signals, while the output winding is supplied with lower frequency oscillations. The high frequency input oscillations produce a flux which greatly increases the impedance in the magnetic core device for the low frequency oscillations, and accordingly small changes in the input current are attended by very much larger changes in the output current. It is in this sense that the magnetic device is termed an amplifier.

Since in the systems disclosed the output current undergoes variations in amplitude corresponding to incoming signaling currents, the magnetic amplifier serves as a modulator.

The circuits of output generator 8, 23 and 42 may, as previously set forth, be tuned to resonance. The change of inductance of the magnetic amplifier windings will alter this condition of resonance and the current in the output circuit be further varied if such tuning is used. However, this is not an essential condition and the output generator circuit may be untuned if desired.

As previously mentioned one effect of the high frequency flux is to decrease the hysteresis energy which must be supplied by the generator in the output circuit of the magnetic amplifier. This effect may, however, be relatively small at the flux densities at which the change in permeability for the low frequency flux is most rapid.

While three specific arrangements involving this invention have been illustrated, it is to be understood that it is capable of general application and that the scope of the invention is to be restricted only by the appended claims.

What is claimed is:

1. The method of transmission which comprises subjecting an alternating current to the action of a magnetic impedance, varying said magnetic impedance in accordance with modulated oscillations of frequency higher than said current whereby said alternating current is varied in magnitude in accordance with the modulations of said oscillations, and transmitting the energy of said varied alternating current to a remote signaling station.

2. The method of amplifying currents which comprises subjecting a magnetic core simultaneously to two alternating magnetic fluxes of different frequency maintaining the lower frequency flux at low density, and varying the value of the higher frequency flux in accordance with changes in the currents.

3. The method of signaling which comprises varying an alternating current in accordance with signals, varying the amplitude of a second alternating current of lower frequency than the first in accordance with the amplitude variations produced in said first-mentioned alternating current, and transmitting to a distant station energy corresponding to that of said varied amplitude current.

4. A magnetic control device comprising a magnetic core, an input circuit and an output circuit associated therewith, a source of high frequency current in the input circuit, a source of lower frequency current in the output circuit, and means connected to said output circuit for transmitting the energy of said lower frequency current to a remote receiving station.

5. An amplifying system comprising a circuit, means for supplying thereto alternating current of a given frequency, a second circuit, means for supplying to said second circuit an alternating current of frequency higher than that supplied to said first circuit, means for varying said higher frequency current, means for varying the impedance of said first circuit in accordance with the amplitude variations produced in said higher frequency current, and means for transmitting the varied energy of the current in said first circuit to a remote point.

6. A magnetic modulator comprising a magnetic core, two alternating current circuits including sources of different frequency currents having windings associated with said core, a signal transmitter in the circuit of the higher frequency current source, and means connected with the circuit of the lower frequency current to transmit the energy thereof to a distant point.

7. A magnetic amplifier comprising two toroidal cores, an input circuit and an output circuit each of said circuits having windings associated with each of said cores, said windings being so related that the electromotive forces induced in said output circuit upon variation of the current of said input circuit are equal in value and opposite in direction, means for impressing an alternating E. M. F. upon said output circuit, means for impressing a higher frequency alternating E. M. F. upon said in-

- pat circuit, and means for transferring to a distant point energy corresponding to that of the current set up in said output circuit by the E. M. F. impressed thereon.
- 5 8. The method which comprises producing carrier waves and higher frequency oscillations, modifying said higher frequency oscillations in accordance with speech, causing said modified oscillations to vary the amplitude of said carrier waves, and transmitting the energy of said varied amplitude carrier waves to a remote station.
- 10 9. The method of increasing the permeability of magnetic material to an alternating flux which consists in maintaining said flux therein at low flux density and simultaneously subjecting the material to a higher frequency flux.
- 15 10. A system for magnifying electrical variations comprising a magnetic material, means for setting up in said material alternating fluxes of two widely different frequencies of such small flux densities that the permeability of the material for the flux of low frequency is increased by the high frequency flux, means for varying the high frequency flux in accordance with said variations to be magnified, and a circuit for translating the resultant changes in permeability into electrical waves modified in accordance with said variations to be magnified.
- 20 11. In combination, a source of carrier waves, a source of higher frequency oscillations, means for modifying said oscillations in accordance with speech, means for varying the amplitude of said carrier waves in accordance with the variations introduced in said oscillations in consequence of said modification, to the practical exclusion of said oscillations and means for transmitting the energy of said varied amplitude carrier waves to a distant point.
- 25 12. A signaling system comprising a magnetic modulator having an input circuit and an output circuit electromagnetically associated with a common magnetic core, means for supplying waves to said output circuit, means for supplying higher frequency speech modified waves to said input circuit to vary the impedance of said output circuit, to control the waves supplied to said output circuit in accordance with speech, and means for preventing transfer of waves of said higher frequency to said output circuit.
- 30 13. In a magnetic modulating system, a circuit for transmitting to a distance, a source of alternating current waves for supplying said circuit, a circuit local to said modulating system containing a source of alternating currents of a frequency high in comparison with the frequency of said first mentioned source, and means for altering the characteristics of said magnetic system to vary the alternating current in the first mentioned circuit comprising means for varying the high frequency current in the local high frequency circuit.
- 35 14. In combination, means for producing periodic current, means for producing alternating current of frequency higher than that of said periodic current, means for controlling said alternating current in accordance with control energy, and means for varying said periodic current in accordance with the control variations in said alternating current and to the practical exclusion of said alternating current.
- 40 15. In witness whereof, I have hereunto subscribed my name this 30th day of March, 1918.
- GUSTAF W. ELMEN.
- In witness whereof, I have hereunto subscribed my name this 2nd day of April, 1918.
